UNITED STATES PATENT OFFICE.

HENRY GOETZ, OF CHICAGO, ILLINOIS.

SLOT AND SLUG FOR VENDING DEVICES.

1,111,793.

Specification of Letters Patent. Patented Sept. 29, 1914.

Application filed July 1, 1912. Serial No. 707,100.

To all whom it may concern:

Be it known that I, HENRY GOETZ, citizen of the United States, residing at Chicago, in the county of Cook and State of Illinois, 5 have invented certain new and useful Improvements in Slots and Slugs for Vending Devices; and I do hereby declare the following to be a full, clear, and exact description of the invention, such as will enable 10 others skilled in the art to which it appertains to make and use the same.

This invention has for its object to provide a device for use on telephone toll-boxes and vending machines whereby the 15 insertion into the same of any except given shapes of slugs particularly adapted to the box or device is prevented whereby fraudulent insertion of counterfeit coins or metal disks is obviated.

20 The invention consists in the features of construction and combinations of parts hereinafter fully described and claimed.

In the accompanying drawings illustrating the invention: Figure —1— is a fragmentary detail vertical section through the coin chute portion of a telephone toll-box or other vending machine equipped with devices embodying my invention. Fig. —2— is a fragmentary view in front elevation of 25 the front wall of a telephone toll-box or the like showing the opening for receiving the coins or slugs equipped with devices embodying my invention. Fig. —3— is a fragmentary rear elevation of the rear wall 30 of the coin slot showing the means for securing thereto the devices embodying my invention. Fig. —4— comprises an end view and a front view respectively, of the slug adapted to be used in connection with 35 the devices disposed in the coin or slug receiving opening of the toll-box or other devices. Fig. —5— is a fragmentary detail horizontal section on the line 5—5 of Fig. —2—. Fig. —6— is a view similar to Fig. 40 —1— showing a modified form of construction.

My device has for its object to provide a coin receiving opening for the coin-chute of a telephone toll-box or other vending machine and a disk or slug therefor provided 45 with coating means whereby only the intended disk or slug may be inserted and fraudulent insertion of disks and counterfeit coins prevented.

50 In the front wall 1 of the housing of a telephone toll-box or other vending machine,

I provide a circular opening 2. Extending parallel with the wall 1 at a distance therefrom substantially equal to the thickness of a coin of the desired denomination adapted for use in the box or device is a wall 3 between which and the wall 1 the coin or slug is adapted to be guided as it drops by gravity into engagement with any suitably coin-operated or coin-controlled means provided in the device. The front wall 1 is provided with a semi-cylindrical flange 4 bordering the opening 2 and extending to the rear wall 3. Secured to said plate or wall 3 and projecting into and through said opening 2 is a member 8 which, in the instance illustrated, consists of a flat plate having projections 9 which are passed through slots or openings 10 in the plate or wall 3 and are flattened out in the manner of rivets to 55 firmly secure said member 8 in place. The said plate or member 8 is preferably vertically disposed in the plane of the vertical diameter of the opening 2 and is of greater width at its upper end than the depth of the wall and its flange 4, the outer or projecting end portion thereof terminating in a projection 11 extending upwardly along the front wall 1. The outer vertical edge of said projection 11 and the contiguous portion of the plate 8 is preferably beveled, as at 12. At its lower end the said plate 8 is provided with a projection or ward 13 which may be circular, as shown, or of any other convenient shape but which projects beyond at least one side face of said plate or member 8. The width of the plate or member 8 between the rear face of the projection or ward 13 and the opposing face of the plate or wall 3 is preferably substantially 60 equal to the thickness of the slug 14 adapted to be used, it being essential, of course, that the latter be freely movable between said plate or wall 3 and the opposing face or faces of said projection or ward 13. The 65 said plate or member 8 is cut away, as at 15, from the point contiguous to the upper end of the projection or ward 13 and to a point in vertical alinement with the front edge of the projection 11, said recess or cut-away portion 15 being of such depth as to render the plate or member 8 of less width immediately above the said projection 13 than the thickness of the slug 14. The said slug 14 is circular and corresponds substantially in 70 diameter with the diameter of the opening 2. It will be understood, of course, that the 75

opening 2 may be of any other shape desired than cylindrical and that the slug 14 may be of a shape and size corresponding to that of the opening 2 so that it may be readily 5 inserted within the latter. As a circular slug is most convenient I have illustrated this shape and a corresponding shape of opening 2 in the drawings. The slug is provided with a recess or slot 16 there- 10 through extending from an edge thereof radially inwardly to any desired depth corresponding with the distance of the upper end of the projection or ward 13 from the point in the wall of the opening 2 in vertical 15 alinement therewith. At least one wall of said recess or slot 16 is provided with a notch corresponding in shape and size with the projection or ward 13 which is adapted to be received therein. In the instance illus- 20 trated the slot 16 terminates at its inner end in a circular opening or notch 17 of greater diameter than the width of the slot but this particular arrangement may be changed and varied without departing from the invention. 25 To insert a slug 14 into the said opening 2 the same is positioned so that the slot or recess 16 therein is vertically disposed and its mouth uppermost and is first placed to receive the projection 11 which is beveled to 30 render insertion easy and is then moved downwardly until it is flush with the opening 2 adapted to receive the same whereupon it may be longitudinally moved into said opening. In this position the opening 35 or notch 17 will register with the projection or ward 13 and in moving the said slug 14 toward the plate or wall 3 said projection or ward 13 will pass through said opening or notch 17. Owing to the depth of the cut- 40 away portion or recess 15 in the plate or member 8 the slug may be moved rear- 45 wardly until it comes in contact with the plate or wall 3 and by then releasing the same it will drop by gravity, and in a direc- 50 tion laterally of its direction of insertion, between said walls 1 and 3.

The device is very simple and efficient enabling the slug to be easily manipulated for insertion into the toll-box or other device for receiving the same.

The particular means herein illustrated and described are capable of being variously modified in substantially the same manner as are locks and keys therefor. In the accom- 55 panying drawings I have illustrated only one specific form of slug and means in the slot adapted to the use of said slug but do not wish to be limited to this specific form as my invention comprehends many modifi- 60 cations thereof falling within the scope of the appended claims.

In Fig. —6— I have shown a modified form of construction in which a sleeve 18 is secured to the rear wall 3 of the chute and 65 projects through the opening 2 in the front

wall thereof, said sleeve being cut away through an arc of about one-hundred-eighty degrees to permit a slug or disk inserted therein to drop in the chute between said walls 1 and 3. The member 8 shown in this 70 figure is identical with that shown in Fig. —1—. This construction is intended to be used in vending machines in which the front wall is devoid of the flange 4 shown in Fig. 1.

75

I claim as my invention:

1. The combination with a chute having substantially parallel front and rear walls and having an opening in its front wall for the admission of a slug, of a slug adapted 80 to slide within said chute, the said slug being slotted transversely of its faces; and a slug selector comprising guides mounted within the said opening and adapted to co-act with the slots in said slug, one of the 85 said guides extending forwardly from the rear wall of the chute and adapted to guide the slug into registration with the bore of the chute, the other of said guides being adapted to hold the slug substantially in 90 transverse alinement with the said opening until the slug registers with the bore of the chute.

2. The combination with a chute having substantially parallel front and rear walls 95 and having an opening in its front wall for the admission of a slug, of a slug adapted to slide within said chute, the said slug being slotted transversely of its faces; and having the slug selector comprising guides mounted 100 within the said opening and adapted to co-act with the slots in the said slug, one of the 105 said guides extending forwardly from the rear wall of the chute and adapted to guide the slug into registration with the bore of the chute, the other of said guides being adapted to hold the slug substantially in 110 transverse alinement with the said opening until the slug registers with the bore of the chute; the former of said guides being cut 115 away to permit the entrance of a finger for digitally pressing the inserted slug into proper position for alining with the said bore of the chute.

3. The combination with a chute having 115 substantially parallel front and rear walls and having an opening in the front wall thereof for admitting a slug in a direction transverse to the face of the slug, of a pair 120 of slug-selecting guides mounted within the said opening transversely of the front wall of the chute, one of the said guides extending substantially to the rear wall of the chute, the other of said guides terminating substantially flush with the forward edge of 125 the bore of the chute; and a slug having a pair of slots transversely of its face adapted to coact respectively with the said guides, whereby both of said guides will hold the slug substantially in transverse alinement 130

with the said opening when the slug is digitally inserted until the slug registers with the bore of the chute, and whereby the latter of said guides will release the slug 5 for admission by gravity into the bore of the chute when the slug has reached the said registering position.

4. The combination with a chute having an opening in one wall thereof for the admission of a disk, and a projection extending into the said opening, and into said chute, said projection comprising a vertically disposed rib having its upper edge disposed in contact with the wall of said opening and provided at its lower end with a 10 ward of less length than said rib, of a disk corresponding in shape and size with said opening and adapted to be inserted therein, there being a slot through said disk extend-

ing inwardly from an edge thereof and laterally enlarged at its inner end for permitting said rib and its ward to pass therethrough in the direction of the longitudinal axis of said slug as the latter is inserted through said opening, said ward terminating 25 in the plane of the inner face of the wall of the chute provided with said opening, whereby when said disk has passed through the latter it will drop by gravity edgewise into said chute.

In testimony whereof I have signed my name in presence of two subscribing witnesses.

HENRY GOETZ.
